H. C. Lind
ATTORNEYS.

UNITED STATES PATENT OFFICE

ERNEST J. SCHUDA, OF ERIE, PENNSYLVANIA, ASSIGNOR TO LOVELL MANUFACTURING COMPANY, OF ERIE, PENNSYLVANIA, A CORPORATION OF PENNSYLVANIA

WRINGER

Application filed May 31, 1930. Serial No. 458,575.

The present invention is directed to an improvement in the construction of sheet metal wringer frames. Such frames are ordinarily supplied with side stiles which carry the bearings for the rolls and when formed of sheet metal may be of box shape having inwardly extending lips on their inner faces which lips terminate at a vertical slot adapted to receive the shafts from the rolls. The frames are usually supplied with guard plates, the purpose of which is to deflect the water leaving the rolls so as to protect the bearings and to assure that this water will reach some means for returning it to the tub. These guard plates have been secured to the side frames by providing the guard plates with ears extending rearwardly through the slots in the stiles, the inner ends of the ears being bent outwardly to engage the inner wall of the stile. With this construction the guard plate is slideable on the stile and while this may assist somewhat in assembly it often happens that the guard plate is shoved up into contact with the wringer roll which is undesirable in that it injures the roll. The inwardly extending ears also form obstructions along the inner edge of the slot. With the present invention the guard plate is fixed against sliding movement relatively to the frame, thus preventing any accidental dislocation of the guard plate and presenting a smooth, even inner surface of the lips. Features and details of the invention will appear from the specification and claims.

A preferred embodiment of the invention is illustrated in the accompanying drawings as follows:

Fig. 1 shows a front elevation of a wringer.

Fig. 2 a section on the line 2—2 in Fig. 1.

Fig. 3 a view from the inner face of the side stile.

Fig. 4 a perspective view of the guard.

Fig. 5 a plan view of the blank from which the guard is made.

Fig. 6 a section on the line 6—6 in Fig. 5.

Fig. 7 a section on the line 7—7 in Fig. 4.

Fig. 8 a view of the inside of the stile with the guard in place.

1 marks the wringer frame base, 2—2 the side stiles, 3 the top bar, and 4 and 5 the

wringer rolls. These are of ordinary construction. The side stiles are of sheet metal of box construction, the inner faces of the stiles having inwardly turned lips 2a terminating in a vertical slot 6 into which shafts 55 7 of the rolls extend. Bearings 8 for the shafts are arranged in the side stiles and the shafts are journaled on these bearings.

A guard plate 9 has a deflecting flange 9a along its sides around the bottom. It is provided with a vertical slot 9b which is adapted to register with the slot 6. It is formed from a blank 9c (see Fig. 5). The edges of the lips 2a have notches 10 and 11 and the guard plate at the edges of the slot 9b has inturned 60 ears 12 and 13. These ears are adapted to register and extend through the notches 10 and 11 respectively. After these ears are in position in the notches 10 and 11 the inner ends of these ears are bent over at 14 on the inner face of the lips 2a, thus securely locking the guard plate in place. The engagement of the shoulders at the ends of the notches with the ears prevents any sliding movement of the guard plate relatively to 65 the stile and the out-turned portions of the ears prevent the disengagement from the 70 lips.

What I claim as new is:

1. In a wringer, the combination of a side 80 stile of box form having inturned lips along its inner face with a roll shaft receiving slot between the lips, said lips having guard plate ear-receiving notches; and a guard plate secured to the stile having ears extending into 85 said notches and headed over on the inside of the stile.

2. In a wringer, the combination of a side 90 stile of box form having inturned lips along its inner face with a roll shaft receiving slot between the lips, said lips having guard plate ear receiving notches along the edges 95 of the lips; and a guard plate secured to the stile having ears extending into said notches and headed over on the inside of the stile, the faces of the ears and the edges of the lips alining.

In testimony whereof I have hereunto set my hand.

ERNEST J. SCHUDA.
